United States Patent

Des. 234,327
Patented Feb. 11, 1975

234,327

LOOM

Marianne S. Rodwell, 114 W. Brown Deer Road,
Milwaukee, Wis. 53217

Filed Apr. 9, 1973, Ser. No. 349,598

Term of patent 14 years

Int. Cl. D15—06

U.S. Cl. D92—15

Fig. 3

Fig. 4

Fig. 5

Fig. 6

FIG. 1 is a side elevational view of a loom showing my new design;

FIG. 2 is a view looking at the right-hand end of FIG. 1;

FIG. 3 is a top view of the loom;

FIG. 4 is a bottom view thereof;

FIG. 5 is a view of the opposite side of the loom from that shown in FIG. 1; and

FIG. 6 is a view of the opposite end from that shown in FIG. 2.

I claim:

The ornamental design for a loom, as shown.
